KNITTING HEAD FOR KNITTING MACHINES

Brooke W. Lerch, Baltimore, Md., assignor to
Western Electric Company, Incorporated, New
York, N. Y., a corporation of New York

Application September 11, 1947, Serial No. 773,426

2 Claims. (Cl. 66—9)

1

This invention relates to knitting heads for knitting machines, and more particularly to knitting heads in which the knitting needles are prevented from being disengaged from the needle jacks during the knitting operations.

In general, knitting heads consist of a plurality of knitting needles which are simultaneously reciprocated and rotated at predetermined speeds so as to combine a plurality of textile threads into a tubular knitted web. This knitted web is utilized in many ways, one of the more common being to apply it as a textile covering around a conductor being continuously advanced along the central axis of the knitting head. The knitting operation of the needles in forming the knitted web creates a definite load or thrust on each of the needles, which depends mainly on the size of the textile threads being used and the type of stitch pattern involved.

Each of the needles is provided with an ear on the lower end thereof which engages a bifurcated end of an associated needle jack by means of which the needles are reciprocated. In knitting heads in use at the present time, substantial portions of the upper ends of the needle jacks are unsupported, and it was found that when the knitting operation employed more than the normal number of threads or slightly heavier gauge threads, or was performed at a higher speed, the load on the knitting needles under such knitting conditions caused the ear of the needle to spring out of the slot in the jack. In addition, centrifugal force acting on the unsupported upper ends of the needle jacks tends to throw the upper ends outwardly, which action may cause the ends of the needles to slip out of the slots in the ends of the needlejacks. Therefore, it is desirable to provide the knitting head with means for preventing the disengagement of the needles and the jacks during knitting operations.

An object of the invention is to provide new and improved knitting heads for knitting machines.

Another object of the invention is to provide a knitting head wherein positive engagement of the knitting needles and needle jacks is maintained regardless of the size threads employed therein or the speed at which a knitting operation is performed.

A knitting head embodying certain features of the invention comprises a jack cylinder having a plurality of needle jacks reciprocably mounted around the periphery thereof, a tubular bearing surrounding the jack cylinder to maintain the

needle jacks in their respective slots and of such length that it supports the upper ends of the needle jacks as they are reciprocated. The upper end of each needle jack is bifurcated to receive the end of a corresponding knitting needle slidably mounted in longitudinal slots provided in a needle cylinder secured in tandem to the jack cylinder. An ear is provided on the bifurcated end of each needle jack which extends upwardly therefrom so as to slidably engage a counterbore provided in a needle bearing secured on the needle cylinder. The needle jack bearing and the counterbore of the knitting needle bearing serve to maintain positive engagement between the needle jacks and the needles during high speed knitting operations or knitting operations which produce a slight overload on the knitting needles.

A clear understanding of the invention will be had from the following detailed description of a specific embodiment thereof, when read in conjunction with the appended drawing, in which the single figure in an enlarged, vertical, sectional view showing a knitting head embodying features of the invention.

Referring now to the drawing, the numeral 10 indicates generally a gear box of a conventional knitting machine (not shown), which is arranged to revolve a jack cylinder 11 and a hollow spindle 12 about the common axis of a knitting head indicated generally at 13. The gear box 10 is arranged to drive the jack cylinder and the spindle in the same direction but at different rates of speed, in accordance with well known principles involved in knitting machine practice. The complete knitting mechanism, to which this invention is applied is disclosed in detail in Lerch et al. Patent 2,236,183 and Brillhart Patent 2,239,378, and only as much of this mechanism is disclosed and described hereinafter as is necessary for a full understanding of the present invention.

A pair of wobbler cams 14—14 are secured angularly to the spindle 12 so that when the spindle is rotated they serve to reciprocate a plurality of needle jacks 15—15 positioned slidably in longitudinal slots 16—16 provided along the periphery of the jack cylinder 11. A tubular bearing 17 is positioned around the jack cylinder 11 to maintain the needle jacks 15—15 in their respective slots as they are reciprocated by the wobbler cams. When the jack cylinder 11 is rotated, the centrifugal force acting on the upper ends of the needle jacks tends to throw the upper ends of the needle jacks outwardly away from the

central axis of the knitting head 13. To support the needle jacks against the effect of this centrifugal force, the upper end of the tubular bearing 17 is extended substantially beyond the upper end of the jack cylinder 11 so that the entire straight portion 18 of the needle jacks 15-15 is supported throughout the entire stroke of the jack from the full line position shown on the drawing to their broken line position.

Each of the needle jacks 15-15 is provided with a bifurcated end 20 arranged to receive an ear 22 formed on the lower end of each of an equal number of knitting needles 23-23 slidably positioned in longitudinal slots 24-24 provided in a needle cylinder 25. The needle cylinder 25 is secured to a tubular hub 26 provided integrally with a head 27 secured to the upper end of the jack cylinder 11, so that the longitudinal slots 24-24 thereof are aligned vertically with the longitudinal slots 16-16 provided in the jack cylinder.

When the jack cylinder 11 and the wobbler cams 14-14 are revolved about the central axis of the knitting head 13 at predetermined speeds, the needle jacks 15-15 are rotated simultaneously about the central axis of the knitting head 13 and reciprocated a predetermined number of times per revolution of the needle cylinder 25. Upon the simultaneous rotation and reciprocation of the knitting needles 23-23, they engage a plurality of textile threads 30-30, which are drawn from suitable supply cops (not shown) and disposed in a symmetrical pattern around the central axis of the needle cylinder, and form a tubular web 31. The tubular web 31 formed by the knitting needles 23-23 may be applied as a covering 32 around a conductor 33 being advanced at a constant rate of speed by a suitable capstan (not shown) through the central bores provided in the needle cylinder 25, the hub 26 of the jack cylinder 11 and the hollow spindle 12.

The knitting operation performed by the needles 23-23 in forming the tubular web 31 produces a working load on each of the knitting needles, which load is transferred longitudinally along the knitting needles to the ears 22-22 which are engaged by the bifurcated ends 20-20 of the needle jacks 15-15. This working load tends to pull the ears 22-22 of the knitting needles out of engagement with the bifurcated ends of the needle jacks. The needle jacks 15-15 must be quite small in cross-section in order to dispose a required number thereof around the periphery of the jack cylinder 11, and because of this small cross-section, they are resilient. In addition, the weight of the needle jack must be held to a substantially low value because they are reciprocated at the high speeds required by the knitting operation. The weight of the jack determines the impact pounding of the bifurcated ends of the ears of the knitting needles, and this action must be maintained at a minimum in order to obtain a long operating life of the knitting head 13.

As a result of this resilient nature of the needle jacks 15-15, slight overloads encountered in the knitting operation of the needles tend to spring the upper ends of the needle jacks outwardly and to disengage the ears 22-22 of the needles from the bifurcated ends thereof. In order to maintain positive engagement of the ears 22-22 within the respective bifurcated end of the needle jacks, vertical ears 34-34 are formed on the bifurcated ends of the needle jacks 15-15, which slidably engage a counterbore 35 provided in a split collar 36. The collar 36 is po-

sitioned in an annular groove 37 provided in the needle cylinder 25 and is maintained in this position by a cup-shaped ring 40. The split collar 36 is provided with an internal bore 41, which acts as a bearing surface for the needles 23-23 as they are reciprocated in their respective longitudinal slots.

The type of knitting operation to be performed by the knitting head 13 is determined by the particular type of insulating covering 32 as it is desired to apply on the conductor 33. In other words, the type of covering selected automatically determines the number of knitting needles 23-23 required, the number and size of textile threads 30-30 to be employed, the speed at which the needle cylinder is to be rotated, and the speed at which the wobbler cams are to be driven in order to provide the proper reciprocation of the needle jacks 15-15 and the needles 23-23. Obviously, it may happen that the selected type of covering 32 may require slightly heavier gauge threads than those used in normal knitting operations. In addition, it may require the use of more textile threads than normally used in the knitting operation or it may require the speed of the knitting operation to be increased. All these factors tend to overload the knitting needles and thereby develop an increased strain on the joints formed by the ears of the knitting needles and the bifurcated end of the needle jacks. In addition, the increased speed of the knitting operation results in a substantial increase in the effect of centrifugal force over that normally acting on the needle jacks. The combination of the increased working load on the needles and the increased centrifugal force acting on the needle jacks tends to spring the ears of the needles out of engagement with the bifurcated ends of their associated needle jacks. However, since the length of the tubular bearing 17 is such that it supports the entire straight portion 18 of the needle jacks during their full operating stroke and the ears 34-34 provided on the bifurcated ends of the needle jacks slidably engage the counterbore 35 of the split collar 36, a positive engagement between the knitting needles and the needle jacks is maintained throughout the knitting operation despite the effect of centrifugal force acting on the upper ends of the needle jacks. In this way the knitting head is rendered capable of performing a wider variety of knitting operations.

What is claimed is:

1. A knitting head for knitting machines including a rotatable jack cylinder having a plurality of longitudinal slots disposed around the periphery thereof, a needle jack slidably positioned in each slot of said needle cylinder, means for simultaneously rotating and reciprocating the needle jacks, a needle cylinder secured in tandem on the upper end of the jack cylinder and having a plurality of longitudinal slots disposed around the periphery thereof which are aligned with the slots in the jack cylinder and a knitting needle slidably positioned in each slot of said needle cylinder, the upper end of each of said needle jacks extending upwardly and converging inwardly to engage the lower end of a corresponding knitting needle, the improvement which comprises a tubular bearing for maintaining the needle jacks in their respective slots when they are rotated and reciprocated, said tubular bearing being of such length that it extends substantially above the jack cylinder to support the portion of the needle jack which is reciprocated above the end of the jack cylinder, an upwardly

extending ear provided on the end of the jack engaging the end of the needle, and an annular bearing provided on the needle cylinder for slidably engaging the ears provided on the end of the needle jacks, whereby the needles are prevented from becoming disengaged from the needle jacks by the action of centrifugal force when the needles and jacks are rotated.

2. A knitting head for knitting machines including a vertically positioned jack cylinder having a plurality of longitudinal slots therein, a needle jack slidably positioned in each slot of said jack cylinder, a needle cylinder secured in tandem on the upper end of the jack cylinder and having a plurality of longitudinal slots therein and aligned with the slots in the jack cylinder and a knitting needle slidably positioned in each slot of said needle cylinder, the upper end of said needle jacks extending upwardly beyond the jack cylinder and converging inwardly so as to engage the lower end of their respective knitting needles, the improvement which comprises an upwardly extending ear formed on the upper end of each jack, a tubular bearing enclosing said jack cylinder and extending above the upper end of the

5

jack cylinder so as to support the entire portions of needle jacks located below the needle cylinder when they are reciprocated to their uppermost position, and an annular bearing positioned on the needle cylinder to hold the needles in their respective slots, said bearing having a counterbore provided therein for slidably engaging the ears provided on the ends of the needle jacks and hold the ends of the needle jacks in engagement with the ends of the knitting needles during a knitting operation.
